UNITED STATES PATENT OFFICE.

CHARLES THORNTON McELVANEY AND EMMETT FRANK LEE, OF DALLAS, TEXAS.

PORTABLE GAS GENERATOR.

Application filed July 6, 1925. Serial No. 41,797.

The present invention relates to a portable gas generator for use with heating tools, and more particularly to a locomotive tire heater.

5 An object of this invention is to provide a portable gas generator of this character which comprises but few parts arranged in condensed form and which may be operated by coal or crude oil and air to produce an 10 intense flame and generate thereby a highly inflammable gas for utilization in tire irons or other tools.

Another object of the invention is to provide a coil heater in which the flame produced by the burning of an admixture of oil and air, is directed in an upward spiral path into contact with a coil so as to play against the exposed surface of the coil and between the helices of the coil to insure an even and 20 thorough heating of the coil and thus effectively utilize the heat generated in the spirally directed flame.

A further object of the invention is to provide a novel system of pipes and valves 25 for controlling the flow of air and oil to a burner coil and to a separate heating coil for the proper combustion of a portion of the oil and air and also for the flashing of a quantity of the admixed oil and air to 30 produce a highly inflammable gas which when burned produces a heat of a very high temperature.

The above and various other objects and 35 advantages of this invention will in part be described in and in part understood from, the following detailed description of the present preferred embodiment, the same being illustrated in the accompanying drawings, wherein:

40 Fig. 1 is a top plan view of a gas producing device constructed according to the present invention.

Fig. 2 is a side elevation of the same.

Fig. 3 is a detail enlarged vertical section 45 taken through the heater of the device.

Fig. 4 is a similar view partly in elevation taken on the line 4—4 of Fig. 3 and axially at right angles thereto, and

50 Fig. 5 is a horizontal section taken through the lower end of the heater on the line 5—5 of Fig. 3 showing the burner coil.

55 Referring to the drawings 10 designates the platform of a truck which may be mounted on wheels 11 to render the device portable. On one end of the platform 10 is

mounted a storage tank 12 for coal oil, crude oil, or the like, to be consumed in the device. The top of the tank 12 is provided with a compressed air connection 13 by means of which air under pressure is admitted to the 60 top of the tank to place the oil under pressure. A blow-off valve 14 is mounted in the side of the tank 12 near its top to relieve the pressure of air when desired. From a point near the bottom of the tank 12 an oil pipe 15 65 is led and provided with a non-return check valve 16 to prevent back flow of oil to the tank. This tank 12 is of sufficient strength to withstand the desired pressure, and the pipe 15 extends from the tank a short distance and is thence carried upwardly and connected by a T coupling 17 or the like to oil branch pipes 18 and 19. The branch pipe 18 is carried downwardly from the T coupling 17 and is provided with a control valve 70 20 and leads along the platform 10 to a gas generator 21 mounted on the other end of the platform. It will be noted that the pipe 18 leads into the lower part of the gas generator 21. The other branch pipe 19 extends 75 from the T coupling 17 to the top of the gas generator 21. An air pipe 22 leads from the air connection 13 and is provided with a non-return check valve 23 to prevent the air from returning to the connection and to the 80 tank. The air pipe 22 is provided with two 85 branches 24 and 25 which lead respectively to the oil pipe branches 18 and 19.

The air branch 24 opens through a T 26 90 into the oil branch 18 beyond the valve 20, and the air branch 25 opens through a T 27 into the oil branch 19 beyond a controlling valve 28 which is mounted in the oil branch 19. The air branch 24 has a controlling valve 29 therein while the air branch 95 25 has a controlling valve 30 therein. In order to facilitate assembling and separation of the various pipes, union couplings 31 may be employed where desired.

As best seen from Figs. 3, 4 and 5, the gas 100 generator 21 comprises an outer casing of cylindrical form closed at its bottom and open at its top. Concentrically disposed within the outer casing is an inner receptacle or cylinder 32 closed at its bottom and open at its top. A heat non-conducting packing 33, of asbestos or the like, is placed between the inner and outer cylindrical members, between the walls and bottoms thereof. A top ring 34 is seated upon the 105 110

upper ends of the cylindrical members to close in the packing 33 and is held in place by stay bolts 35 which extend vertically through the packing, the ring 34 and the platform 10 for holding the parts together and for securing the heater to the platform.

Seated in the bottom of the receptacle or inner cylindrical member 32 is a burner coil 36 which is of spiral form and has one end 10 projecting through the side of the gas generator 21 and connected to the oil branch pipe 18.

The inner end 37 of the burner coil 36 is open for the purpose of emitting a spray of 15 the oil and air as hereinafter described. Arranged above the burner coil 36 is a helical heating or flashing coil 38 which may extend to the top of the gas generator 21 and has its upper end connected to the oil branch 20 pipe 19. The convolutions of the heating coil 38 are slightly spaced apart so as to expose the adjacent surfaces thereof to the flame which rises through the gas generator 21. The lower portion of the heating coil 25 38 rests upon the outer convolution of the burner coil 36, and the lower end of the heating coil 38 is carried outwardly through one side of the gas generator 21 for connection 30 to a tire iron or other tool used for the consumption of a highly inflammable gas.

The operation of the gas generator is as follows: The tank 12 is filled to the desired height with coal oil, and air under pressure is introduced through the connection 13 by 35 a hose or the like from the blower lines and compressors with which shops are usually supplied. A small portion of waste is ignited and thrown down into the top of the gas generator 21. The air under pressure in the tank 12 forces oil therefrom through pipe 15, check valve 16 and into the branch pipes 18 and 19. The valve 20 is opened to the desired extent to allow a supply of the oil to flow through the pipe 18 into the burner coil 36.

At the same time the valve 29 is opened to admit air under pressure from the pipe 22 through branch pipe 24 in to the oil pipe 18 to commingle with the oil and produce a 50 combustible mixture. This mixture is emitted from the open end 37 of the burner coil 36 and is given a spiral swirling movement as it is ignited and burned so that the flame travels upwardly in a spiral path and 55 is impinged against the spaced convolutions of the heating coil 38. By regulating the valves 20 and 29 the desired pressure is obtained in the burner coil 36 so that the issuing spray is given the desired volume and impetus, and the proportions of the admixture regulated to secure the best results. The gas generator 21 is given a cylindrical 60 form in order to insure the spiral upward travel of the flame to uniformly heat the coil 65 38.

The coil 38 may be heated to the desired temperature, and when so heated the valves 28 and 30 are opened so as to admit an admixture of the oil and air into the top of the coil 38. This admixture of oil and air, entering the heated coil 38 is flashed into a highly inflammable gas which is carried downwardly through the coil 38 and raised in temperature during such passage, and finally is carried out through the bottom of 75 the gas generator 21 for use in tire irons or other tools used for applying high degrees of temperature to the tires of locomotives, or the like.

It is of course understood that various 80 changes and modifications may be made in the details of construction and design of the above specifically described form of the gas generator without departing from the spirit of the invention, such changes and modifications being restricted only by the scope of 85 the following claims.

What is claimed is:—

1. In a portable gas generator, the combination of an oil tank, a gas generator, an oil supply line connecting said oil tank and said gas generator, an air supply line connected to said oil supply line intermediate the oil tank and the gas generator for atomizing the oil, said gas generator comprising 95 a heat insulated casing, a gas generating coil mounted within the casing, and a burner mounted in the casing and below the gas generating coil.

2. A portable gas generator comprising 100 the combination of an oil supply tank, a gas generator, a movable platform adapted to carry said oil supply tank and gas generator, means for connecting said oil supply tank and gas generator, said connecting means 105 being adapted to supply oil to the gas generator, and a compressed air line connected to the oil line intermediate the oil tank and the gas generator, said gas generator comprising a heat insulated casing, a helical gas 110 generating coil mounted within the insulated casing, and a burner mounted in the casing and below the helical coil, said burner being adapted to project a helical flame against 115 said helical coil.

3. A portable gas generator comprising the combination of an oil supply tank, a gas generator, a movable platform adapted to carry said oil supply tank and gas generator, an oil supply line connecting said oil supply 120 tank and gas generator, an air line connecting said oil line intermediate said oil supply tank and gas generator, said gas generator comprising a heat insulated casing, a helical gas generating coil mounted within the casing and having an inlet and an outlet 125 through the casing, and a helical coil burner mounted in the casing and below the helical coil.

4. A portable gas generator comprising 130

the unitary combination of an oil supply tank, a gas generator, an oil supply line joining said oil tank and gas generator, and an air line connected to said oil line intermediate the oil tank and gas generator, said gas generator comprising a heat insulated casing, a helical gas generating coil mounted

within the heat insulated casing, and a coil burner mounted within the casing and below the gas generator coil, said burner being adapted to impart a swirling motion to the flame projected therefrom.

CHARLES THORNTON McELVANEY.

EMMETT FRANK LEE.
